UNITED STATES PATENT OFFICE.

CHARLES BRISBINE, OF LISBON, NORTH DAKOTA.

FUSIBLE LINK.

1,272,369.

Specification of Letters Patent. Patented July 16, 1918.

Application filed June 5, 1917. Serial No. 173,013.

To all whom it may concern:

Be it known that I, CHARLES BRISBINE, a citizen of the United States, residing at Lisbon, in the county of Ransom and State 5 of North Dakota, have invented certain new and useful Improvements in Fusible Links, of which the following is a specification.

This invention relates to links and more particularly to a fusible link of the type 10 employed as part of a flexible connection for releasing the valves or other parts of an automatic fire extinguisher system, or for the purpose of releasing fire doors, windows, etc., when a predetermined degree of temperature 15 has been reached.

The object of the invention is to provide a link of the type mentioned including a pair of members having twisted ends adapted to be interlocked by a slight turning 20 movement and secured in an interlocked position by means of solder or other fusible binding means.

Another object of the invention is to provide a link of the type mentioned including 25 a pair of interlocking link members adapted to be secured together with sufficient firmness to withstand all necessary strain but arranged to separate quickly at a predetermined degree of temperature.

30 The above and other objects and advantages of this invention will be in part described and in part understood from the following description of the present preferred embodiment, the same being illustrated in 35 the accompanying drawings in which:

Figure 1 is a view of the two link members previous to assembling.

Fig. 2 is a view showing the members in interlocking position, and

40 Fig. 3 is a view similar to Fig. 2 illustrating the method of binding the interlocking members together.

As shown in the drawings, my improved link is composed of two separate rods or 45 link members indicated respectively by the numerals 1 and 2. Each of the said rods 1 and 2 has one end thereof looped and twisted in the manner shown to form an eye 3. The opposite end of each of said rods 50 is formed with a spiral twist as indicated at 4 and in forming the complete link the spirally twisted ends of the two rods are interlocked as shown in Figs. 2 and 3 and are secured in interlocked position by means

of an application of solder 5 or other fusible 55 binding means.

In the practical use thereof, the link is connected by means of the eyes 3 to a cord, chain or other flexible connection forming part of an apparatus for releasing fire doors, 60 windows, etc. In this connection it will be appreciated that the interlocked ends, bound together by the solder 5 will hold the two members of the link together firmly enough to withstand the necessary strain as long as 65 the solder remains unaffected by heat. But, however, as soon as a predetermined degree of temperature is reached the solder fuses thus allowing the two link members to readily separate.

70 Owing to their spiral formation a slight turning movement is necessary to connect the ends of the members in the interlocking position shown in Figs. 2 and 3. When the ends of the two members have been engaged 75 and given the slight turning movement necessary to interlock the same the solder or other fusible binding means is then applied as has been described and serves to normally prevent the link members from having the 80 reverse turning movement necessary in separating. In this connection therefore it will be appreciated that the strain is exerted on the interlocked ends of the link members and not upon the fusible binder only in so 85 far as the binder resists the tendency of the link members to turn and separate.

89 From the foregoing, it will be seen that I have provided an improved link in which the two separate link members thereof are 90 locked together with sufficient firmness to withstand the necessary strain as long as they are prevented from having the slight turning movement necessary to separate. The solder or other fusible agent forms a 95 binder which will effectually prevent the link members from separating until a predetermined degree of temperature has been attained.

100 It is to be understood that I have disclosed only the preferred embodiment and that I reserve the right to make such changes in the invention as are desirable and come within the scope of the appended claims without departing from the spirit thereof. 105

I claim:—

1. A fusible link, which comprises a pair of links each composed of a single piece of

material and having an eye formed at one end, the opposite ends of the links adapted for interlocking engagement by a rotative movement; and fusible means around said 5 interlocking ends.

2. A fusible link, comprising a pair of link members having openings formed in one end thereof the opposite ends of said members being twisted and adapted to be interlocked by a slight turning movement, and fusible means for binding said interlocked 10 ends together.

3. A fusible link, comprising a pair of locked members having openings formed in 15 one of their ends, the opposite ends of said members being spirally twisted and adapted to be interlocked, and fusible means for binding said interlocked ends together.

4. A fusible link, including a pair of rods, each of said rods having one end looped and 20 twisted to provide an eye, the opposite ends of said rods having a spiral twist and adapted to be interlocked, and fusible means for holding said interlocked ends together.

5. A link comprising a pair of separable 25 link members adapted to be locked together at one end by a slight rotative movement and fusible binding means surrounding said interlocked ends.

In testimony whereof I affix my signature 30 in presence of two witnesses.

CHARLES BRISBINE.
